ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

TRAIN CONTROL SYSTEM

Application filed December 18, 1922. Serial No. 607,688.

This invention relates to a train control system and more particularly to a system for controlling the movement of trains automatically by roadside mechanism and manually by the engineman on the train, and has special reference to the provision of a system in which automatic control is so combined with manual control as to assure absolute safety while permitting proper dispatch in the movement of trains.

One of the principal objects of my present invention comprehends the provision of a train control system in which train carried mechanism for governing the operation of the train is automatically controlled by roadside mechanism operable in accordance with roadside conditions in such a manner that the running operation of the train under unsafe traffic conditions is made dependent upon such traffic conditions only so as to provide absolute safety in train operation, and in which the co-operative control by the engineman is necessitated to supplement the automatic control for producing efficient and expeditious train movement.

In the production of an efficient train control system one of the factors of paramount importance is that of providing for the element of absolute safety of train movement under unsafe traffic conditions. To accomplish this it is requisite that a roadside mechanism reflecting the conditions on the roadside should assume unchallenged predominance in controlling the behaviour of the train under hazardous conditions, and that any condition of control impressed or imposed on an unsafely moving vehicle by the roadside mechanism should be beyond human interference. Another desideratum of infinite importance, however, is that of providing a system in which the engineman is restrained from shifting or casting the full burden of control upon the automatic train control mechanism, substitution of the automatic mechanism alone for the engineman being highly undesirable in practice. The ideal mode of controlling the movement of trains is that in which the engineman is compelled to be alert, or is deterred or restrained

handling of the train is enforced and in which the engineman is supplanted by the automatic control mechanism only upon his failure to properly discharge his duties, and in which when so supplanted the automatic control is the dominant factor until safe running conditions of the train is resumed and the engineman again assumes control. When the engineman and the automatic train control mechanism are made to co-operate in this manner, the one acting as a check upon the other, absolute safety and proper dispatch in the running of trains is assured.

By my present invention to accomplish this object I provide a train control system in which full control of the train is left in the hands of the engineman so long as he is properly performing his duties in obedience to and in conformity with the indications of the roadside signalling apparatus, in which the control of the train is automatically taken from the engineman who is incapacitated or remiss in the performance of his duties and the train is automatically operated in accordance with roadside conditions, and in which the engineman is compelled to be alert and to again take charge of the operation of the train in order to avoid an undesirable condition of train control, the system thus combining the factor of absolute safety by making train operation dependent upon the automatic dictation of the roadside mechanism under hazardous conditions with the factor of proper train dispatching by making the efficient movement of the train dependent upon the activity and alertness of the engineman.

Another principal object of the present invention relates to the provision of a train control system in which the movement of the vehicle is controlled within the limits of three permissible speeds including a maximum speed beyond which the vehicle cannot run, a medium speed under which the vehicle must approach points of danger and run in localities where a greater speed would be unsafe, and a low speed above which the vehicle cannot run in unsafe localities, as in blocks occupied by other trains. In accomplishing this object of the invention, the de-

sign and construction of the system is such that if a speed greater than the predetermined maximum speed is attempted the train is automatically controlled to cause a retardation of the speed to and below the predetermined maximum limit, and if a speed greater than the medium speed is attempted when roadside conditions require the movement of the vehicle under the medium speed, 10 the train is automatically controlled to retard the speed to or below the predetermined medium limit, and if a speed greater than the low speed is attempted when the roadside conditions require a low speed restriction on 15 the train, the train is automatically controlled for compelling movement of the train at or under the said predetermined low speed.

In the train control system of my present invention, a roadside mechanism is employed 20 for controlling the operation of a train carried mechanism, the said roadside mechanism including a means for transmitting energy from the roadside to the vehicle under "safe" operating conditions and for inhibiting 25 the transmission of energy under "danger" operating conditions. Since the energy transmitting means on the roadside is the controlling element and the automatic dictator of the manner in which the train should 30 be operated, it is highly essential that the operation of such energy transmitting means be rendered absolutely safe and dependable. It is therefore a further principal object of 35 the present invention to provide a roadside mechanism in which the parts are so constructed and inter-related that the possibility of defective behaviour of the energy transmitting means is reduced to a minimum, and that any existing defect in such transmitting 40 means be indicated to the engineman by the block signalling system so that he may control or operate his train accordingly.

Further and ancillary objects of the present invention are the provision of a system in 45 which a warning is given to the engineman by an audible signal when the exhausting of air from the brake pipe takes place in the event of an automatic application of the brakes; the provision of a train control 50 system in which the roadside mechanism for controlling the movement of the train and the roadside signalling apparatus are under the control of track switch means for diverting movement of the train from a main track 55 to a passing track siding, so that when it is desired to divert the motion of the train the train control mechanism and the signalling apparatus are operated to produce restrictive 60 train running; and the general provision of 65 a train control system of this nature in which the manifold functions desired to be accomplished may be obtained by apparatus of relatively simple construction.

To the accomplishment of the foregoing 65 and such other objects as may hereinafter ap-

pear, my invention consists in the elements and their relation one to the other, as hereinafter particularly described and sought to be defined in the claims, reference being had to the accompanying drawing showing the preferred embodiment of my invention, and in which:

Figure 1 is a diagrammatic view showing the vehicle carried apparatus and circuits and the roadside apparatus and circuits for one block, and

Figure 2 is a view of a chart showing how the train may be operated by the engineman under personal control without the intervention of the automatic train control if the engineman is properly discharging his duties, and showing the manner in which the train is automatically controlled in the event that the engineman is remiss in his duties.

In the train control system of my present invention, for directly controlling the movement of the train there is provided an electro-responsive device for controlling the operation of the air brake system, the said electro-responsive device being under the control of cooperating train and roadside mechanism and being operated thereby in accordance with roadside conditions. The electro-responsive device comprises in the preferred

construction an electromagnet 20 which controls the operation of a combined reservoir and brake valve 21 of the type disclosed in my Patent No. 1,411,526 of April 4, 1922, and in the copending application of Allen B. Kendall Serial No. 443,046 of February 7, 1921, the said reservoir and brake valve being interposed between the main reservoir 22 of the air brake system and the engineman's brake valve 23, and being connected thereto by means of the piping 24 and 25 respectively, the said reservoir and brake valve 21 including a reservoir valve which

under normal conditions permits the free flow of reservoir air from the main reservoir 22 to the engineman's brake valve 23, and which under unsafe running conditions of the train is closed to cut off the supply of air from the main reservoir to the engineman's brake valve. The combined reservoir and brake valve 21 is also connected by means of the pipe 26 to the brake pipe of the air brake system and by means of a pipe 27 to an exhaust control valve mechanism 28 such as is disclosed and claimed in my copending application Serial No. 292,548, the said exhaust control valve 28 being connected by means of the piping 29 to the pipe 24 leading from the main reservoir 22, the construction and operation of these parts being such that under normal running conditions of the train the brake valve of the valve mechanism 21 is closed to prevent venting communication between the air brake system and the exhaust control valve 28, and under abnormal running conditions of the train the said valve

is opened to effect intercommunication between the pipes 26 and 27 for the venting of the brake pipe of the train through the exhaust control valve 28 to atmosphere. In the present construction, there is also provided an audible signal such as a whistle 30 which connects to the exhaust of the exhaust control valve 28 by means of a pipe 31 so that the engineman is warned or apprised by sounding of the audible signal of the exhausting of air from the brake pipe in case of an automatic application of the brakes.

For the purpose of rendering the automatic control mechanism inactive, as when it is desired to run the train without automatic control, there is provided a by-pass 32 connecting the pipes 24 and 25, the said by-pass being controlled by a cock 33 which is normally closed and which is shown in closed position in Figure 1, the opening of the valve 33 permitting the free flow of reservoir air from the main reservoir 22 to the engineman's brake valve 23 irrespective of any operation 25 of the reservoir and brake valve 21; and there is also provided a cock 34 in the piping 26, the said cock being normally open and being closed when it is desired to render inoperative the control of the brake valve of the reservoir and brake valve 21.

As disclosed in my above mentioned patent, in the operation of the system the electromagnet 20 is energized under "safe" roadside conditions and is deenergized under unsafe roadside conditions to effect the desired operations of the reservoir and brake valve mechanism 21. For directly controlling the operation of the electromagnet 20 there is provided a train carried circuit which is normally energized by a train carried source of energy such as the battery 35, the said circuit including the resistance r leading from the positive terminal of the battery 35, conductors 36, 37, 38, 39, 40, electromagnet 20, conductor 41, movable contact 42 which is movable to any of a plurality of positions as shown in Figure 1, and which normally occupies the inclined full line position as shown in said figure, the contact point 43, conductor 44, contact point Z, a speed circuit controller 45 connected to the wheels of the vehicle and operated thereby, a common contact point 46, and conductor 47 to the negative terminal of the battery 35. With this construction, it will be seen that this controlling circuit is normally closed for effecting the energization of the electromagnet 20 when the contact 42 is in the full line position as indicated, and when the circuit controller contacts Z and 46 are bridged by the circuit controller 45. The contact 42 is closed as hereinbefore referred to, and as will be described presently in detail when the train is running under safe roadside conditions, and the contacts Z and 46 of the speed circuit con-

troller are so adjusted to keep this circuit closed when the train is running below a predetermined maximum speed such for example as 70 miles an hour and to open the circuit when the speed of the train exceeds this predetermined maximum.

To control the behaviour of the contact 42, there is provided cooperating train and roadside mechanism which functions to cause the said contact 42 to be maintained or held in its full line position under safe traffic conditions and to cause the same to move to either of the dotted line positions shown in response to unsafe traffic conditions. The train and roadside mechanism for controlling the action of the contact 42 includes the provision of a roadside energy transmitting device which in the present form of my invention comprises a plurality of ramp rails spaced along the roadside, a rail such as indicated

at 48 being provided for each section or block of the track, the said ramp rail comprising means for transmitting energy to a train carried shoe mechanism 49 under safe roadside conditions, such energy being transmitted to a translating device such as a relay 50, the action of which directly controls the operation of the contact 42. Under normal running conditions of the train with the train running between ramp rails, the translating device 50 which may comprise a relay of the type disclosed in the copending application of A. B. Kendall Serial No. 404,375 of August 18, 1920, and which includes an electromagnet locking device 51, is energized by the train carried battery 35 through a local circuit including the said battery, the resistance r , conductor 36, a conductor 52, relay contact 53 in the full line position shown, conductor 54, contacts 55 and 56 normally bridged by switch element 57 attached to for movement with the shoe 49, conductor 58, the relay and relay lock 50 and 51, conductor 59, contacts 60 and 61 normally bridged by the switch element 62 attached to for movement with the shoe 49, the conductor 63, the relay contact 64 in the full line position shown, and conductor 65 to the negative pole of the battery 35.

When the train passes a ramp under safe roadside conditions, the translating relay 50 is controlled by the cooperation of the shoe 49 and the ramp 48, the cooperation being such that as the shoe 49 rides over the ramp 48 the normally closed local train circuit for relay 50 is opened and another circuit substituted therefor, which other circuit is operated in response to roadside or traffic conditions. The substituted circuit comprises a partial roadside circuit which is connected to the ramp 48 and a partial train carried circuit which is connected to the shoe 49, the two partial circuits combining to form a completed circuit for operating the relay 50. In the present construction the partial roadside circuit includes essentially a roadside

source of energy such as the battery 66, a pole changer including the movable contacts 67 and 68 under the control of a relay D, a circuit make and break device 69 under the control of a relay H, and one of the track rails T, the said circuit being traced from the ramp 48 by the conductor 70, the contact 68, the front contact point 71, the conductor 72, the battery 66, conductors 73 and 74, the front contact point 75, the contact 67, the conductor 76, a relay 77, the conductors 78 and 79, contact 69, conductors 80 and 81, a normally closed switch 82 and a conductor 83 connected to one of the rails T. The partial cooperating vehicle circuit may be traced from the shoe 49 which contacts the ramp 48 through the conductor 84, a contact 85 which is connected to the contact 56 by means of the switch element 57 bridging the same when the shoe 49 is raised by engagement with the ramp 48, the contact 56, the conductor 58, the relay and lock therefor 50 and 51, the conductor 59, the contact 60, the contact 86 connected thereto by means of the switch element 62 which bridges these contacts upon elevation of the shoe 49, and conductor 87 connected to the framework of the vehicle. With this construction and arrangement, it will be evident that when the shoe 49 engages a ramp 48 the relay 50 will be controlled by a circuit which is completed by the engagement of the shoe 49 and a ramp 48 and the electrical connection between the framework of the vehicle and a track rail T. Under normal running conditions of the vehicle, the contacts 67 and 68 of the roadside pole changer are in the position as shown in Figure 1, contacting with the front contact points 75 and 71 respectively, and under this condition the cooperating vehicle and roadside partial circuits form a completed closed circuit for energizing the relay 50 with current of a given polarity or direction to hold or maintain the relay contacts such as 53, 64 and 42 in the full line position shown in the drawing. With this construction it will be furthermore apparent that as the shoe 49 leaves the ramp 48 under "clear" roadside conditions, the local or vehicle circuit for controlling the relay 50 will be replaced for the combined roadside and vehicle partial circuits for energizing the said relay to maintain the contacts thereof in the normal full line position.

As hereinbefore referred to, one of the principal objects of the present invention relates to the provision of a train control system in which the train is automatically controlled by the roadside mechanism without opposition or interference by the engineman of the train so that any automatic dictation made by the roadside mechanism cannot be cancelled by the intervention of the engineman, this to produce a factor of absolute safety in train control, and in which the engineman for the proper dispatch of the train

is compelled to cooperate with the automatic mechanism, thus providing a system in which automatic operation and manual control by the engineman are combined to reduce the risks resulting from any possible defective operation of the train control mechanism or improper behavior on the part of the engineman and to provide for expeditious movement of trains without sacrifice of safety. To produce the desired results the factor of safe operation of the train is made solely dependent upon the action of the automatic mechanism and the factor of dispatch and expeditious train operation is made solely dependent upon the alertness of the engineman. To this end in the operation of my system the train and track mechanisms are made to cooperate under any unsafe roadside condition, such for example as under "caution" or "danger" roadside conditions, to produce a stopping effect on the train, the engineman being called upon to modify the control of the train and track mechanism and to forestall a complete or full stop by a positive act on his part, such forestalling, however, being made impossible until the train stopping effect has been initiated and until such a stage of the effect has been reached as is consistent with a safe running operation of the train under the particular roadside condition then effective. More specifically, in the system of my present invention, full control of the train is left in the hands of the engineman who is properly discharging his duties, and only as a consequence of non-observance by the engineman of the indications of the roadside signalling apparatus, is the train automatically controlled to bring the same to a stop, and the engineman is then compelled to be alert and to intervene to forestall a full stop, such forestalling being rendered operative or possible only when a safe running condition of the train is reached, the elements of safety and dispatch being thus combined by preventing opposition or cancellation of automatic train control under unsafe running conditions and by preventing the engineman from relying solely upon the operation of the automatic train control mechanism, and compelling him to be alert at all times.

To accomplish these objects of my invention and to bring the train to a halt under "caution" and "danger" track conditions, the contact 42 is so controlled as to effect the opening of the circuit for controlling the action of the magnet 20 under both "caution" and "danger" roadside conditions, the said contact being moved to the inclined dotted line position and to the vertical dotted line position under such "caution" and "danger" conditions respectively.

For effecting the movement of the contact 42 to the inclined dotted line position under "caution" track conditions, the relay 50 is

energized by a current of a direction opposite to that of the normal energizing current, the relay 50 comprising to this end a three-position relay of the type where with current transmitted in one direction to the coil thereof, the contacts will be moved and held in one position as shown in the full lines in Figure 1; while with the current transmitted in a reverse direction the contacts will be moved and held in another position as shown by the inclined dotted lines in the figure; and where with no current transmitted for energizing the relay, the contacts will move to the vertical or neutral dotted line position shown in the figure. Under "caution" track conditions the relay 50 is energized by current of an opposite direction or polarity when the shoe 49 contacts the ramp 48, the combined circuit formed by the partial roadside and vehicle circuits controlling the action of the relay being energized from the roadside battery 66 with current flowing in a direction opposite to the normal flow thereof, this reversal of direction of current being accomplished by movement of the contacts 67 and 68 of the roadside pole changer effecting the opening of the front contact points 75 and 71 respectively and the closing of the back contact points 88 and 89 respectively, this operation being accomplished by the de-energization of the relay D as will be described hereinafter. When the shoe 49 leaves the ramp 48 under these "caution" conditions, the relay 50 remains energized by a current of opposite polarity, this relay being thereafter controlled by the vehicle battery 35 and energized by means of the circuit including the resistance r , conductors 36 and 37, conductor 90, contact 64 in the oblique dotted line position, conductor 63, contacts 61 and 60, conductor 59, the relay lock and relay 51 and 50, conductor 58, contacts 56 and 55, conductor 54, contact 53 in oblique dotted line position, and conductors 91 and 65. The contact 42, however, when moved to the oblique dotted line position, maintains the circuit controlling the valve electromagnet 20 open and the said electromagnet deenergized to bring the vehicle to a halt.

For the purpose of forestalling a complete stopping of the vehicle, I provide a manually operable forestalling mechanism which when operated by the engineman will close a second circuit for controlling the action of the valve electromagnet 20 and for placing the same under the control of the speed of the vehicle so that a medium speed running may be permitted under such conditions, the said second circuit being operable, however, only after the stop effect has been initiated and when the speed of the vehicle has been reduced to or below the said medium limit so that forestalling is made possible only after a safe running operation of the vehicle has been attained. To this end, I

provide the manually operable forestalling mechanism generally designated as 92 which in the present construction comprises a stick relay switch, means so manually controlled as to be operable only by a single impulse, the said stick relay switch including an electromagnet 93, a plurality of contacts 94 and 95, and a manually operable single impulse push button control 96 which under normal conditions assumes the position shown in Figure 1 with the contacts 94 and 95 open and which may be operated when the safe running operation of the train is reached to energize the valve electromagnet 20, this single impulse operated stick relay being preferably of a construction as disclosed in my copending application Serial No. 634,053, filed April 23, 1923. In this construction the single impulse relay comprises a slidable stem or plunger 97 movable from the normally descended position shown to an ascended position for engaging and moving the contacts 94 and 95 and the receptacle-shaped push button device 96 which contains a fluid, the plunger 97 being provided with a bottom disk or piston shaped member slightly spaced from the walls of the push button receptacle 96, the construction being such that when the push button 96 is operated to an ascended position a single impulse will be transmitted to the plunger 97 and the latter will thereafter be free to move to descended position whether or not the push button receptacle is held in ascended position or released for movement to the descended position. When the push button 96 is operated to close the contacts, the fluid in the receptacle acts against the piston of the plunger to transmit the operation to move the plunger and the contacts to the ascended position, the plunger being thereafter free to gravitate since the fluid contained in the receptacle 96 gradually seeps through the clearance provided between the piston and the receptacle wall.

When the train carried circuits are automatically operated under "caution" track conditions and when the train has been reduced to a predetermined medium speed, the push button 96 is actuated by the engineman to forestall a full stop, and by actuating the push button 96 the contacts 94 and 95 are elevated by means of the plunger 97, the contact 94 being effective for closing a holding or stick circuit for energizing the electromagnet 93, the said circuit comprising the vehicle battery 35, the resistance r , conductors 36, 37, 38 and 39, a conductor 98, the coil of the electromagnet 93, conductor 99, contact 94 closed by the ascending movement of the plunger 97, conductor 100, conductor 101, a contact Y adjusted so that when the train is running above a predetermined medium speed the said contact is open as shown in the drawing and when the train is run-

ning at or below the predetermined medium speed the said contact engages the speed circuit controller 45 for closing the circuit to the common contact 46 and conductor 47 to the battery 35. This circuit, therefore, when the train is running above a medium speed as under normal conditions, will cause the deenergization of the stick relay electromagnet 93 and the opening of the contact 94 so 10 that the stick relay assumes the condition as indicated in Figure 1. With this construction it will be furthermore seen that the closing of this circuit is rendered possible only when the train is moving below the 15 predetermined medium speed or when the train has been reduced to such speed.

When the safe running speed of the vehicle has been attained and upon manual operation of the medium speed release key 96, 20 the contacts 94 and 95 are held in elevated position, the contact 94 closing the stick circuit as described and the contact 95 closing a circuit for controlling the operation of the electromagnet under the control of the speed 25 of the vehicle by means of the circuit comprising the battery 35, the resistance r , the conductors 36, 37, 38, 39 and 40, electromagnet 20, conductor 41, a conductor 102 leading to a contact or make and break device 103 also controlled by the three-position relay 30, the said contact under the "caution" conditions being in the oblique dotted line position for engaging the contact point 104, the circuit further including the conductor 105, the contact point 106, contact 95 closed, the conductors 100 and 101, contact Y closed when the train has reached the predetermined medium speed, contact point 46 and conductor 47 to battery 35. With this controlling 35 circuit it will therefore be seen that when the roadside ramp 48 indicates "caution" and transmits a "caution" indication to the relay 50 for causing the opening of the circuit to the electromagnet 20 for applying the brakes, the vehicle will be brought to a halt unless the engineman operates the 40 forestalling button or push key 96, the action of the circuits controlled by the forestalling relay 92 being rendered operative only after the stop effect for bringing the vehicle to a halt has been initiated; and only after a predetermined stage of such stop effect has been reached corresponding to safe 45 running conditions under "caution" roadside conditions, such as the predetermined medium speed for which the contact Y is adjusted.

It will be further seen that when the train 50 is running under a "caution" restriction and the medium speed is exceeded, the stick relay 93 will be deenergized necessitating reduction of the speed of the train and another manual operation of the push key 96.

It is deemed advisable that when an engineman of a train obeys the indications of the

roadside signalling apparatus, not only should no automatic application of the brakes take place on entering a "caution" block, but it should not be necessary for the engineman to operate a forestalling device to avoid an automatic application under such conditions. To accomplish this result I have found it desirable to control the stick relay 93 by a shunt circuit including the conductor 107, the contact 108 which is closed under 70 normal conditions only, and the conductor 109, the said conductors and contact comprising a shunt across the contact 94 and conductor 99 so that when the train is running at a speed below the predetermined 75 medium speed, relay 93 is energized to close the stick circuit controlling the same and to close the circuit embracing the electromagnet 20 and the speed circuit controller 45, so that it will be possible for a train to approach and enter a "caution" block when the speed of the vehicle is below the predetermined medium limit without an automatic application of the brakes taking place, and without the necessity of operating the 80 forestalling mechanism, the circuit controlled by the forestalling device 92 being automatically substituted for the normal circuit controlling the operation of the electromagnet 20. With this construction, it will be seen, however, that if after passing the "caution" ramp the prescribed medium speed is exceeded, then an automatic application 85 will take place by the opening of the circuit at the contact Y, and to prevent a full stop it will be necessary for the engineman to reduce the speed of the train and to operate the medium speed forestalling device. 90

By the provision of the above described 95 circuits, it will be seen that under normal running conditions of the train the operation thereof is under the full control of the engineman, and that under unsafe traffic conditions and improper handling of the train, the train is automatically controlled in response to 100 roadside or traffic conditions without the possibility of any intervention on the part of the engineman for interfering with or cancelling the action of the train control mechanism, intervention of the engineman, however, being necessitated to prevent an undesirable stop under "caution" track conditions, a positive act on the part of the engineman being thus required to forestall 105 the stop, with the act of forestalling being rendered possible only after safe running 110 conditions of the train have been resumed, automatic control of the train being in this manner combined with manual control thereof to provide for expeditious operation of 115 the train without any sacrifice of safety. 120

For effecting the movement of the contact 125 42 and the other relay contacts to neutral vertical dotted line position under "danger" track conditions the partial roadside circuit

connected to the ramp is opened by the opening of the contact 69 controlled by the relay H as heretofore mentioned and as will be described more in detail hereinafter, the opening of this partial circuit preventing any transmission of energy to the vehicle relay 50, the said relay 50 being deenergized by the elevation of the shoe 49 when the same rides the ramp 48, the contacts controlled by the relay 50 thereby moving to the neutral dotted line position. As heretofore mentioned, the movement of the contacts to the neutral position, and especially the contact 42, effects the opening of the controlling circuit to the electromagnet 20 for deenergizing the said electromagnet to apply the brakes and bring the vehicle to a halt. For the purpose of forestalling a complete or full stop under these "danger" operating conditions, my invention further includes the provision of a second forestalling mechanism generally designated as 92' operable manually by the engineman to forestall a complete stop and to substitute therefor a different controlling condition for the movement of the vehicle, such for example as a predetermined low speed restrictive condition. The forestalling mechanism 92' is also preferably a single impulse controlled stick relay switch of the type heretofore described comprising an electromagnet 93', a plurality of contacts 94' and 95' therefor, a manually operable push button 96' provided for effecting the movement of a plunger 97' connected to the contacts 94' and 95', the said forestalling mechanism being operable to close controlling circuits under prescribed conditions which involve an automatic operation of the train carried mechanism to initiate a "stop" effect of the vehicle and the reaching of a predetermined stage of said effect, as when the vehicle has been reduced or is running below a predetermined speed. Under these prescribed conditions when the push button 96' is operated to elevate the plunger 97', contact 94' will be momentarily closed to close the circuit comprising the train carried battery 35, resistance r, conductors 36, 37 and 38, conductor 98', coil of relay 93', conductor 99', contact 94', conductors 100' and 101' contact X which is open when the speed of the train exceeds a predetermined low limit and which is closed by the speed circuit controller 45 when the speed is at or below said predetermined limit, this circuit being closed by the contact 46 and conductor 47 to the battery 35. Thus when the speed of the train is below the predetermined low limit the relay coil 93' will be energized for holding the contact 94' in closed condition so that this circuit is maintained closed, the construction being such that when the speed of the train exceeds this predetermined low limit the circuit will be opened at the contact X and the relay coil 93' deenergized for opening the contacts 94' and 95'. When the circuit is maintained closed, however, the contact 95' is in a position for closing another circuit to control the operation of the valve electromagnet 20, the said valve being placed under the control of the predetermined low speed of the vehicle and more specifically under the control of the speed circuit controller 45 and the low speed contact X thereof by means of the circuit which comprises the train carried battery 35, resistance r, conductors 36, 37, 38, 39 and 40, electromagnet 20, conductors 41 and 102, contact 103 in vertical dotted line position engaging a contact element 110, conductor 111, contact point 106', contact 95', conductors 100' and 101', contact X, speed circuit controller 45, contact 46, and conductor 47 to the battery 35, this circuit when closed, as after the predetermined low speed has been reached and the forestalling mechanism 92' has been operated, effecting the energization of the electromagnet 20 for permitting the release of the brakes. It will be evident from the circuit arrangement shown and described that if after the brakes are released when the full stop is thus forestalled, the speed of the train is made to exceed the predetermined low limit, the described controlling circuit for the electromagnet 20 will be opened at the contact X and the brakes again applied, necessitating again a reduction of the speed of the train to or below the said predetermined low limit, and another manual operation of the forestalling mechanism 92' to effect a release of the brakes.

With the above described mechanism it will be found that the vehicle carried mechanism is operated automatically by the roadside mechanism under "caution" and "danger" track conditions to produce a desired effect such as a "stop" effect in the condition of the vehicle, forestalling means being provided operable under "caution" roadside conditions for forestalling the full stop, the said forestalling means being rendered active, however, only after the operation of the mechanism has initiated the "stop" effect and after a safe stage of said effect has been reached, the forestalling operation being effective for substituting for the "stop" effect a safe speed control effect, a second and independent manually operated forestalling means being provided under "danger" conditions to forestall the full stop, the second forestalling means being also rendered active only after the operation of the train and roadside mechanism has initiated the "stop" effect and only after another stage of said effect which is safe under "danger" conditions has been reached, the forestalling means being effective for substituting a different speed control effect for the "stop" effect produced, forestalling of an undesirable train action being therefore rendered possible only after safe running conditions of the train have been established, it being impossible

to oppose or cancel the automatic dictation of the roadside mechanism and the intervention of the engineman being necessitated so as to compel alertness on his part to keep the train moving.

5 For the purpose of indicating high, medium and low speed conditions of the train circuits, and for the purpose of advising the engineman when these speeds are made, as a 10 guide to the operation of the manually operable forestalling means, I provide a plurality of cab signals connected to the speed control circuits and rendered operative thereby. To these ends for the high speed circuit there is 15 provided a signal Z^2 which is connected across the conductors 40 and 44 so that when the speed controller Z is closed, this signal will be energized, and when the speed controller contact Z is opened, this signal will be 20 deenergized to indicate the speed conditions. For the medium speed circuit, I provide a second signal Y^2 connecting the conductor 39 to a back contact 106a of the relay contact 95, the signal Y^2 being energized when the 25 speed controller contact Y is closed, as when the train runs at or below the medium predetermined speed. Thus this signal will be a means for indicating to the engineman when the forestalling means should be operated, 30 and will also indicate whether or not the stick circuit of the relay 93 has been made or closed by the operation of said forestalling means. Similarly, for the low speed a signal X^2 is provided which is connected between 35 the conductor 38 and a back contact 106b of the armature contact 95', the signal X^2 being energized when the train reaches the predetermined low speed and the speed controller contact X is closed. The signal X^2 therefore 40 also comprises a means for guiding the engineman in the operation of the low speed forestalling means, and forms a means for indicating whether the stick circuit to the relay 93' has been made after actuation of the 45 forestalling means.

As heretofore mentioned, a further principal object of the present invention comprehends the production of a track or roadside mechanism in which the probability of 50 improper behaviour thereof is reduced to a minimum, and in which any defective action therein is made known to the engineman so that he may properly control the operation of his train, the invention more specifically 55 comprehending the provision of a roadside mechanism which is so inter-related with a block signalling system that both the roadside mechanism and the block signalling system are made dependent upon each other, thus 60 avoiding those improper or false operations which are at times inherent in the signal itself, the roadside mechanism and the signal mechanism being furthermore so interlocked that any defects in the roadside mechanism 65 are indicated by the signal mechanism, and

so that conversely the behaviour of the signal mechanism is reflected in the indications of the roadside mechanism.

To accomplish these results, the partial circuit to the ramp 48 heretofore referred to 70 is controlled by the relays H and D which comprise in the present form of my invention home and distant relays respectively, the operation of the roadside signal 112 being 75 also controlled by the home and distant relays H and D, the relay H representing the condition of the block immediately in advance of the signal 112, and the relay D representing the condition of the block second in advance of the signal 112. The relay H is controlled by the track relay 113 of 80 the next succeeding block, the said track relay being connected as usual across the rails T of the said block, the track rails being subdivided into a plurality of sections or blocks in accordance with the usual practice by means of the insulated joints J, the track relays being fed by means of track batteries 114 provided for each block, the track relay controlling the operation of a contact 115 connected in a circuit including 85 the home relay H, the said circuit comprising a conductor 116, conductor 117, relay H, conductor 118, contact 115, conductor 119, the contact 120 controlled by a circuit controlling switch 121 to be described in detail hereinafter, and a conductor 122 leading through the various relays and switch circuit controller contacts and battery, as is well understood in automatic block signalling. The 90 distant relay D is controlled by the relay H of a given and the next succeeding block by means of the circuit including the conductor 116, conductor 123, relay D, conductor 124, contact 125 controlled by the home relay H, and a conductor 126 leading into the block through the circuit controller of the signal in advance, and through the battery as is the usual practice in automatic block signalling. In operation under "danger" conditions, as when a train is present in the block 95 in advance, the home relay H will be deenergized by the short circuiting of the track magnet 113, this effecting the opening of the contacts controlled by the relay H and the deenergizing of the relay D for operating the pole changer contacts 67-68; and under "caution" track conditions the relay D alone 100 will be deenergized for operating the pole changer contacts 67 and 68, this action of the relays under "danger" and "caution" conditions being effective for opening and reversing circuit connections respectively in the partial circuit to the ramp 48 for producing 105 the desired control of the vehicle carried mechanism as hereinbefore detailed.

For operating the signal 112 by the controlling relays H and D, there is provided preferably in the partial circuit leading to the ramp 48, the electromagnet 77 control- 110

ling a contact 127 forming part of the circuit including the conductor 128, operating and holding mechanism of the signal 112, a signal battery 129, and a conductor 130; a 5 second contact 131 under the control of the distant relay D being provided for controlling the opening and closing of another circuit to the signal 112, the said circuit including the battery 129, conductor 130, conductor 10 132, contact 131, and conductor 133 to the operating and holding mechanism of the signal 112. By this construction when the control relay H is deenergized, as under "danger" conditions, the electromagnet 77 is also de- 15 energized and the contacts 127 and 131 are opened to cause the signal 112 to move to "danger" position, and when the relay D alone is deenergized under "caution" conditions the contact 131 is opened to cause the signal 112 to move to "caution" position.

For indicating on the signal mechanism any defective behaviour in the roadside mechanism, I provide means for detecting the integrity of the ramp 48 and the circuits controlling the same, the said means comprising a normally closed detecting circuit which includes roadside battery 66, the conductor 72, contact point 71, the pole changing contact 68, the conductor 70, the ramp 48, a conductor 134 leading from the ramp, conductor 80, contact 69, conductors 79 and 78, relay 77, conductor 76, contact 67, contact point 75, conductors 74 and 73 to battery 66. When the ramp is destroyed or any part of this circuit broken, this circuit will be opened to cause the deenergization of electromagnet 77 and the opening of the contact 127 controlled thereby, causing the signal 112 to move to "danger" position, any defect in the ramp 40 or in the circuit controlling the same being by this means indicated in the signalling mechanism.

For conversely indicating in the ramp 48 any defective operation of the signal mechanism 45 112, as when the signal improperly indicates a "danger" condition, there is provided the switch contact 82 heretofore referred to, the said contact being connected for movement with the signal 112, the said switch contact 82 being movable over an arcuate contact element 135 for keeping the partial circuit of the ramp closed when the signal indicates "clear" or "caution" and for opening this circuit when the signal is at a 50 "stop" or "danger" position.

By the cooperation of the above recited roadside circuits, therefore, it will be obvious that the ramp controlling circuit and the signal controlling circuits are made directly 55 dependent upon the same controlling elements, thus eliminating the dependency of the ramp circuit on the signalling circuits to avoid improper or false operations inherent in the signalling apparatus from influencing the action of the ramp, the ramp and signal

being so inter-related and interlocked that an improper behaviour of one is reflected and will be indicated in the other.

The system of my present invention further includes the provision of means for controlling the operation of the roadside mechanism and the roadside signalling means for producing a restrictive running of the train when it is desired to move the same from the main track T to a passing siding PT. To 70 this end there is provided the switch circuit controller 121 heretofore referred to, the said switch circuit controller being connected to a track switch means 136 and being operative when the passing siding PT is connected to the main track T for opening the contact 120 and for closing a contact 137, opening of the contact 120 being effective for deenergizing the relay H and for consequently deenergizing the relay D, the closing 75 of the switch contact 137 being effective for producing "caution" conditions in the roadside and signalling mechanism. By the closing of the contact 137 the relay 77 is energized by means of the circuit including the battery 66, conductor 72, back contact 88, contact 67, conductor 76, electromagnet 77, conductor 78, the conductor 138, contact 137, the conductor 139, the contact 140 controlled by the track relay 113, conductor 141, conductors 81 and 85 80 134, ramp 48, conductor 70, contact 68, back contact point 89, and conductor 73 to battery 66; and by closing this circuit and the energization of the magnet 77 the contact 127 controlled thereby is closed, and this with the 85 opening of the contact 131 due to the deenergization of the control relay D effects the movement of the signal 112 to "caution" position to indicate a speed restriction for movement of the train from the main track to 90 the siding track. Under this condition of operation, the ramp 48 is energized so as to operate the train carried mechanism to place the same under speed restrictive control, the said ramp being energized by the circuit including the battery 66, the conductor 72, back contact point 88, contact 67, conductor 76, electromagnet 77, conductors 78 and 138, contact 137, conductor 139, contact 140, conductor 141, the contact switch 82 closed under 95 110 "caution" conditions, and conductor 83 to the rail T, the circuit being closed through the train partial circuit, the ramp 48, conductor 70, contact 68, back contact point 89 and conductor 73 to the battery 66.

Referring now to Figure 2 of the drawing, I show a diagram of the manner of controlling the speed of the train equipped with my automatic train control mechanism, this diagram illustrating the operation of the 115 train when controlled by the engineman and when controlled automatically. In this figure the speeds controlled by the contacts X, Y and Z referred to in Fig. 1 are represented by actual numerical value, such as 120

15 miles per hour for low speed, 30 miles per hour for medium speed, and approximately 70 miles per hour for maximum speed. The curve shown by the heavy line 0—1—2—3—
5 4—5—6—7 represents the limiting speed at
which the train may run under the conditions shown. If the speed is exceeded at any point on this curve, an automatic application of the brakes will take place; while if the
10 engineman operates under this limiting speed in obedience to the indications of the roadside signalling mechanism, then the automatic train control will not act to take away the control of the train from the engineman.
15 This is illustrated by the broken line curve 0A—8—9—10—11—12—7A, and if the speed of the train is held to this curve, then automatic application of the air brakes does not take place.

20 The lines T—T represent the railway track, J—J the insulating joints in the rails of the track T—T dividing the same into sections or blocks as BO, BA, BB, BC, BD and BE. In the diagrammatic illustration these
25 blocks are shown protected by two position home and distant signals on the same mast, as for example A2 and A' for block BA, B2 and B' for block BB, C2 and C' for block BC, etc. It is obvious that single arm semaphore signals of the three-position type would answer the same purpose, giving the same
30 indications.

For each block there is provided a ramp rail as shown, the ramp A being provided for
35 the block BA, ramp B for the block BB, ramp C for the block BC, etc. These ramps are located in proximity to the various signals with which they are connected as indicated. The block BC is assumed to be occupied so that the signal C'—C2 for this block indicates "stop". The next preceding block BB is accordingly a "caution" block, and the signal B'—B2 thereof indicates "caution"; while the second preceding block BA
40 is accordingly a "clear" block, the signal A'—A2 thereof indicating "safety" conditions. Similarly, the signals D'—D2 and E'—E2 for the blocks BD and BE indicate "clear" track conditions ahead. Under these
45 conditions, therefore, the ramp B is in a condition to transmit the indication of "caution" to the vehicle, the ramp C is in a condition to transmit the indication of "stop" to the vehicle, and the ramp D is in a condition to transmit the indication of "clear" to the vehicle.

The method of operation and control of the train by the present train control system may be conveniently followed from the curve
50 shown in Fig. 2. If the vehicle is operated just at or under the maximum limiting speed, as along the line 0—1, the train will proceed without an automatic application of the brakes taking place. If the engineman
55 should attempt to exceed this maximum lim-

iting speed, then an automatic application of the brakes will take place, the controlling circuit for the electromagnet 20 being opened at the contact Z. Just as soon, however, as the speed is reduced, the contact Z is again
70 made and the electromagnet 20 energized, and the condition for automatic application is thus relieved so that the engineman may operate his brake valve to recharge the brake pipe of his train and continue under the maximum speed.

If the train is proceeding at or just under the maximum speed to the "caution" ramp B in disregard or violation of the indication of the signal indication B'—B2, then an automatic application takes place, so that the speed of the train is retarded as represented by the curve 1—2. When the medium speed of 30 miles per hour is reached, as at the point 2, the engineman may continue at or just under the 30 mile speed instead of having his train brought to a stop by operating forestalling mechanism 92, and by the operation of this mechanism the circuits for medium speed running are established to effect
85 the energization of the electromagnet 20 and to place the same under the control of the medium speed running of the train.

In operating the medium speed forestalling mechanism and thereafter operating the
90 brake valve to release the brakes which have been applied on the train, a short interval of time is consumed so that the speed of the train is retarded and then accelerated to the point 9 illustrated by the loop X'. It is assumed that the engineman now being alert, will prefer not to have a further automatic application of his brakes take place, and therefore he will proceed with his train as
95 represented by the broken line 9—10—11—12, operating the low speed forestalling mechanism 92' when the speed is reduced to the low prescribed rate so that when shoe 49 of the vehicle contacts the "danger" ramp C, no
100 application of the brakes takes place.

If the engineman does not proceed along the broken line 9—10—11—12, but allows the speed of the train to return to the line 2—3, and proceeds along this line to the ramp C, then another automatic application of the
105 brakes takes place, retarding the train as represented by the curve 3—5. If when this point is reached the engineman operates the low speed forestalling mechanism 92', the full stop may be forestalled and the train may proceed under the low limiting speed; and if the train is operated to continue under the low limiting speed, as along the lines
110 11—12, further automatic application will be avoided, and if this speed is again exceeded, an automatic application will again take place, necessitating again a reduction in speed and a further operation of the forestalling mechanism. When the point 5 is reached
115 in the speed of the train, an interval of time
120

is consumed in the operation of the low speed forestalling mechanism and in the releasing of the air brakes on the train, so that the speed of the train conforms somewhat to the loop Y'.

If on receiving the automatic "stop" application at the ramp C the engineman makes no attempt to operate the low speed forestalling mechanism, the train will be brought

- 10 to a stop as indicated by the speed curve 3-5-4. When this takes place, the train may proceed when the engineman operates the forestalling mechanism 92', and the speed of the train can be accelerated along the curve 15 2' to the point 11, and the train may continue without further automatic application if the broken dotted line 11-12 is followed.

Since block BD is clear as illustrated by the indications of the signal D'-D2, then 20 ramp D is in a condition to restore normal running conditions to the train upon contact of the shoe 49 with the ramp D, and the engineman may thereafter accelerate the speed of his train along the curve 6-7, the engineman keeping the speed of his train somewhat under the maximum speed so that the train speed will be accelerated to the point 25 6A and continue thereafter along the line 6A-7A just below the maximum permissible 30 speed.

While I have shown my device in the preferred form, it will be obvious that many changes and modifications may be made in the structure disclosed without departing 35 from the spirit of the invention, defined in the following claims.

I claim:

1. A manual-automatic speed control system, in combination, a vehicle carried electrically operated device, mechanism including vehicle carried and roadside means operated in response to normal or "clear" roadside conditions for producing a normal state of operation and operated in response 40 to a "non-clear" roadside condition for producing another state of operation of said device and vehicle carried means for restoring the normal state of operation of said device and for placing the same under the control of the 45 speed of the train under the said "non-clear" roadside conditions comprising a means normally inoperative and rendered operative when said mechanism is operated in response to the "non-clear" condition, a speed controlled means and a manually operable means, all of 50 which combinedly control the restoration of said electrically operated device, the said manually operable means being in turn under the control of the said speed controlled means, under both "clear" and "caution" operations 55 of said mechanism.

2. A manual-automatic speed control system, in combination, a vehicle carried electrically operated device, mechanism including 60 vehicle carried and roadside means operated

in response to normal or "clear" roadside conditions for producing a normal state of operation and operated in response to a "non-clear" roadside condition for producing another state of operation of said device and 70 vehicle carried means for restoring the normal state of operation of said device and for placing the same under the control of the speed of the train under the said "non-clear" roadside conditions comprising a make and 75 break means normally inoperative and rendered operative when said mechanism is operated in response to the "non-clear" condition, a speed controlled contact device and a manually operable contact device, all of 80 which combinedly control the restoration of said electrically operated device, the said manually operable device being in turn under the control of the said speed controlled device, and a single indicating means under 85 the control of said manually operable contact device.

3. A manual-automatic speed control system, in combination, a vehicle carried electrically operated device, mechanism including 90 vehicle carried and roadside means operated in response to normal or "clear" roadside conditions for producing a normal state of operation and operated in response to a "caution" roadside condition for producing 95 another state of operation of said device and vehicle carried means for restoring the normal state of operation of said device and for placing the same under the control of the speed of the train under the said "caution" 100 roadside conditions comprising a means normally inoperative and rendered operative when said mechanism is operated in response to the "caution" condition, a speed controlled means and a manually operable means, all of 105 which combinedly control the restoration of said electrically operated device, the said manually operable means being in turn under the control of the said speed controlled means, under both "clear" and "caution" operations 110 of said mechanism.

4. A manual-automatic speed control system, in combination, a vehicle carried electrically operated device, mechanism including vehicle carried and roadside means operated 115 in response to normal or "clear" roadside conditions for producing a normal state of operation and operated in response to a "caution" and a "danger" roadside condition for producing another state of operation of said device and vehicle carried means for restoring the normal state of operation of said device and for placing the same under the control of the speed of the train under either of the said "caution" or "danger" roadside conditions comprising means normally inoperative and rendered operative when said mechanism is operated in response to the "caution" or "danger" condition, a speed controlled means and manually operable means, all of 120 125 130

which combinedly control the restoration of said electrically operated device, the said manually operable means being in turn under the control of the said speed controlled means for both "caution" and "danger" roadside conditions.

5. A manual-automatic speed control system, in combination, a brake valve magnet, mechanism including a vehicle carried controlling relay, a vehicle carried shoe and a roadside ramp operated in response to normal or "clear" roadside conditions for producing a normal state of operation and operated in response to a "non-clear" roadside 10 condition for producing another state of operation of said magnet and vehicle carried means for restoring the normal state of operation of said magnet and for placing the same under the control of the speed of the 15 train under the said "non-clear" roadside conditions comprising a circuit controlling means normally inoperative and rendered operative when said relay is operated in response to the "non-clear" condition, a speed 20 controlled means and a manually operable single impulse responsive means, all of which combinedly control the restoration of said electrically operated device, the said manually operable single impulse responsive 25 means being in turn under the control of the said speed controlled means.

6. A manual-automatic train control system, in combination, an electrically operated vehicle control device, a vehicle circuit therefor for normally energizing the same, means including roadside mechanism active for opening said circuit to effect deenergization of said device, and vehicle means for re-energizing said device comprising a second circuit including a make and break device closed upon the opening of the first circuit, a speed controlled contact device closed when the train reaches a speed below a predetermined limit, and a switch means closed by a manual 40 operation of the engineman, the said switch means including instrumentalities under the control of the speed controlled contact device, and a signal indicating means under the control of said switch means.

5. A manual-automatic train control system, in combination, an electrically operated vehicle control device, a vehicle circuit therefor for normally energizing the same, means including roadside mechanism active for opening said circuit to effect deenergization of said device, and vehicle means for re-energizing said device comprising a second circuit including a make and break device closed upon the opening of the first circuit, a speed controlled contact device closed when the train reaches a speed below a predetermined limit, and a single impulse responsive switch means closed by a manual operation 60 of the engineman, the said single impulse re-

sponsive switch means including instrumentalities under the control of the speed controlled contact device and operative for maintaining the switch means in position to hold the second circuit closed only when the speed controlled contact device is closed.

8. A manual-automatic train control system, in combination, an electrically operated vehicle control device, a vehicle circuit therefor for normally energizing the same, means including roadside mechanism active for opening the said circuit to effect deenergization of said device and vehicle means for re-energizing said device comprising a second circuit including a make and break device closed upon the opening of the first circuit, a speed controlled contact device closed when the train reaches a speed below a predetermined limit and a mechanically operable single impulse responsive switch means closed by a manual operation of the engineman and openable by a break in the circuit at the said speed controlled device.

9. In a manual-automatic train control system, in combination, an electrically operated vehicle control device, a vehicle circuit therefor for normally energizing the same, means including roadside mechanism active for opening the said circuit to effect the deenergization of said device, and vehicle means for reenergizing said device comprising a second circuit including a make and break device closed upon the opening of the first circuit, a speed controlled contact device closed when the train reaches a speed below a predetermined limit, and a single impulse responsive stick relay switch means closed by a manual operation of the engineman.

10. A manual-automatic train control system, in combination, an electrically operated vehicle control device, a vehicle circuit therefor for normally maintaining the said device in a given condition, means including roadside mechanism active for operating the said circuit to change the condition of the said device, and vehicle means for returning the said device to its normal condition comprising circuit control instrumentalities including a make and break device controlled upon the operation of the said circuit, a speed controlled contact device closed only when the train is proceeding below a given speed, and a single impulse responsive switch means closed only by a manual operation and openable automatically by the opening of the said speed controlled contact device, whereby the said vehicle control device after the automatic operation thereof may be restored to its normal condition when the train reaches a speed below a predetermined limit and when the engineman operates the switch.

11. In a manual-automatic vehicle control system, in combination, vehicle carried mech-

- anism, means including roadside mechanism for automatically operating said vehicle carried mechanism under "caution" and "danger" track conditions to produce a predetermined effect in the condition of the vehicle, manually operable means under the control of the speed of the train for forestalling the production of such effect, and single indicating means under the control of said manually operable means.
12. In a manual-automatic vehicle control system, in combination, vehicle carried mechanism, means including roadside mechanism for automatically operating said vehicle carried mechanism under "caution" and "danger" track conditions to produce a predetermined effect in the condition of the vehicle, a speed controlled means and manually operable single impulse responsive means under the control of the speed controlled means for forestalling the production of such effect under proper vehicle speed restrictive conditions.
13. In a train control system, in combination, an electrically operated vehicle control device, a vehicle circuit therefor for normally energizing the same, provisions including roadside mechanism active for opening the said circuit to effect de-energization of said device, and vehicle provisions for re-energizing the said device comprising a second circuit including a make and break device closed upon the opening of the first circuit, a speed controlled contact device closed when the train reaches a speed below a predetermined limit, and a single impulse responsive switch means closed by a manual operation of the engineman, and instrumentalities for holding said switch means closed only when the said contact device is closed.
14. In a train control system, in combination, an electrically operated vehicle control device, a vehicle circuit therefor for normally energizing the same, provisions including roadside mechanism active for opening the said circuit to effect de-energization of said device, and vehicle provisions for re-energizing the said device comprising a second circuit including a make and break device closed upon the opening of the first circuit, a speed controlled contact device closed when the train reaches a speed below a predetermined limit, and a switch means closed by a manual operation of the engineman, said switch means being connected in circuit to the speed controlled contact device so as to be always under the control of the latter.
15. In a train control system, in combination, an electrically operated vehicle control device, a vehicle circuit therefor for normally energizing the same, provisions including roadside mechanism active for opening the said circuit to effect de-energization of said device, and vehicle provisions for re-energizing the said device comprising a second circuit including a make and break device closed upon the opening of the first circuit, a speed controlled contact device closed when the train reaches a speed below a predetermined limit, and a manually operable stick relay switch means, and signal indicating means under the control of said stick relay switch means.
16. In a train control system, in combination, an electrically operated vehicle control device, a vehicle circuit therefor for normally maintaining the said device in a given condition, provisions including roadside mechanism active for operating the said circuit to change the condition of the said device, and vehicle provisions for returning the said device to its normal condition comprising circuit control instrumentalities including a make and break device controlled upon the operation of said circuit, a speed controlled contact device closed only when the train is proceeding below a given speed, and a switch means closed only by a manual operation and held closed only when the said speed controlled contact device is closed, whereby the said vehicle control device after an automatic operation thereof may be restored to its normal condition when the train reaches a speed below a predetermined limit and when the engineman operates the switch, and signal indicating means under the control of said switch means.
17. In a train control system, in combination, an electrically operated vehicle control device, a vehicle circuit therefor for normally maintaining the said device in a given condition, provisions including roadside mechanism active for operating the said circuit to change the condition of the said device, and vehicle provisions for returning the said device to its normal condition comprising circuit control instrumentalities including a make and break device controlled upon the operation of said circuit, a speed controlled contact device closed only when the train is proceeding below a given speed, and a mechanically operable single impulse responsive switch means closed only by a manual operation and openable automatically by the opening of said speed controlled contact device, whereby the said vehicle control device after an automatic operation thereof may be restored to its normal condition when the train reaches a speed below a predetermined limit and when the engineman operates the switch.
18. The combination in a train control system with a vehicle carried mechanism including a train control means, of a roadside mechanism comprising an energy transmitting device, an energizing circuit therefor, roadside signalling apparatus, means controlled by roadside conditions for operating both the signalling apparatus and the energizing circuit to indicate such roadside conditions, detecting means connecting said energizing circuit

and said signalling apparatus operable upon defective behaviour of the circuit to operate the signalling apparatus to indicate such defect therein, and detecting means connecting the signalling apparatus with the said circuit for indicating in the said circuit the behaviour of the said signalling apparatus.

19. The combination in a train control system with a vehicle carried mechanism including a train control means, of a roadside mechanism comprising an energy transmitting device, an energizing circuit therefor, roadside signalling apparatus including circuit means therefor, means controlled by roadside conditions for operating both the signalling circuit means and the energizing circuit to indicate such roadside conditions, detecting means connecting said energizing circuit and said signalling circuit means operable upon defective behaviour of the energizing circuit to operate the signalling apparatus to indicate such defect therein, and detecting means connecting the signalling apparatus with the said energizing circuit for indicating in the said circuit the behaviour of the said signalling apparatus.

20. The combination in a train control system with a vehicle carried mechanism including a train control means, of a roadside mechanism comprising a ramp, an energizing circuit therefor, roadside signalling apparatus, means controlled by roadside conditions for operating both the signalling apparatus and the energizing circuit to indicate such roadside conditions, detecting means connecting said energizing circuit and said signalling apparatus operable upon defective behaviour of the circuit to operate the signalling apparatus to indicate such defect therein, and detecting means connecting the signalling apparatus with the said circuit for indicating in the said circuit the behaviour of the said signalling apparatus.

21. The combination in a train control system with a vehicle carried mechanism including a train control means, of a roadside mechanism comprising an energy transmitting device, an energizing circuit therefore including a source of energy and circuit changing means, roadside signalling apparatus, means controlled by roadside conditions for operating the signalling apparatus and for operating the circuit changing means to reverse the direction of flow of and to discontinue the current therein, a detecting circuit for said energy transmitting device, means connecting said detecting circuit and said roadside signalling apparatus operable upon opening of the said circuit to operate the signalling apparatus, and detecting means connecting the signalling apparatus with said energizing circuit for indicating in said circuit the behaviour of the signalling apparatus.

22. The combination in a train control system with a vehicle carried mechanism includ-

ing a train control means, of a roadside mechanism comprising an energy transmitting device, a partial energizing circuit therefor including a source of energy and a pole changer, a roadside signalling apparatus, means controlled by roadside conditions for operating the signalling apparatus and for operating the partial circuit to reverse the direction of flow of and to discontinue the current therein under "caution" and "danger" track conditions respectively, a detecting circuit for said energy transmitting device, means connecting said detecting circuit and said roadside signalling apparatus operable upon opening of the said circuit to operate the signalling apparatus, and detecting means connecting the signalling apparatus with said partial circuit for indicating in said partial circuit the behaviour of the signalling apparatus.

23. The combination in a train control system with a vehicle carried mechanism including a train control means, of a roadside mechanism comprising a ramp, an energizing partial circuit therefor including a source of energy, a pole changer and a track rail, roadside signalling apparatus including signalling circuits, means controlled by roadside conditions for operating the signalling circuits to indicate caution and danger track conditions and for operating the partial circuit to reverse the direction of flow of and to discontinue the current therein under caution and danger conditions respectively, a detecting circuit for said ramp, a relay connecting said detecting circuit and said roadside signalling circuits operable upon opening of the said detecting circuit to operate the signalling apparatus, and detecting means including a switch connecting the signalling apparatus with said partial circuit for indicating in said partial circuit the behaviour of the signalling apparatus.

24. The combination in a train control system with the track rails, of roadside mechanism comprising an energy transmitting device, an energizing circuit therefore, roadside signalling apparatus, means controlled by conditions on the track rails for operating both the signalling apparatus and the energizing circuit to indicate such conditions therein, and provisions interconnecting the energy transmitting device and the signalling apparatus for indicating in the latter a defective behaviour of the former, and for indicating in the former the defective behaviour of the latter.

25. The combination in a train control system with main track rails and siding track rails, of roadside mechanism comprising an energy transmitting device, an energizing circuit therefore, roadside signalling apparatus, means controlled by conditions on the main track rails for operating both the signalling apparatus and the energizing circuit to indicate such conditions therein, provisions in-

- terconnecting the energy transmitting device and the signalling apparatus for indicating in the latter a defective behaviour of the former, and for indicating in the former the behaviour of the latter, and means controlled by the conditions of the siding track rails for operating both the signalling apparatus and the energy transmitting device to produce predetermined indications therein.
26. The combination in a train control system with main track rails and siding track rails, of roadside mechanism comprising an energy transmitting device, an energizing circuit therefor, roadside signalling apparatus, means controlled by conditions on the main track rails for operating both the signalling apparatus and the energizing circuit to indicate clear, caution and danger roadside conditions therein, provisions interconnecting the energy transmitting device and the signalling apparatus for indicating in the latter a defective behaviour of the former, and for indicating in the former the behaviour of the latter, and means controlled by the conditions of the siding track rails for operating both the signalling apparatus and the energy transmitting device to produce clear and caution indications therein.
27. In an automatic train control system, the combination with trackway means automatically conditioned in accordance with traffic conditions, of train control apparatus on a vehicle governed thereby and comprising a normally energized electrically operable brake control device acting when de-energized to cause an automatic application of the brakes of the vehicle, a stick relay, an energizing circuit for said brake control device including contacts governed by said stick relay and maintained closed if said relay is energized, speed contacts operated by a speed-responsive device driven from the wheels of the vehicle and open when the vehicle is traveling at excessive speed, an energizing circuit for said stick relay including said speed contacts, and manually controllable means for determining the closure of said energizing circuit for the stick relay at one point, said manually controllable means normally maintaining said circuit open and being effective to close said circuit for a limited time only after each manual operation.
28. In a train control system for railroads having a track divided into blocks, each provided with a normally closed track circuit, a wayside signal at the entrance to each block controlled by the track circuits of blocks in advance, an impulse transmitting device on the track near each signal for cooperating with vehicle-carried means to govern movement of the vehicle, a control circuit for each device for governing the controlling condition of said device, means automatically controlled in accordance with traffic conditions for rendering said control circuit inoperative,
- a checking circuit and a source of current associated with each of said devices and including part of its control circuit, electro-responsive means in said checking circuit for governing the corresponding wayside signal, and other means automatically controlled in accordance with traffic conditions for opening said checking circuit, whereby said electro-responsive means cannot be energized and the corresponding wayside signal indicate clear if there is an interruption in that part of the control circuit for the corresponding impulse transmitting device included in the checking of that device.
- Signed at Chicago, in the county of Cook, and State of Illinois, this 23rd day of November, A. D. 1922.
- ARCHIBALD G. SHAVER.
